UNITED STATES PATENT OFFICE.

JOHN FLEISCHMANN, OF BALTIMORE, MARYLAND.

MACHINE FOR POLISHING OR SMOOTHING MOLDINGS.

SPECIFICATION forming part of Letters Patent No. 423,748, dated March 18, 1890.

Application filed September 4, 1889. Serial No. 322,963. (No model.)

To all whom it may concern:

Be it known that I, JOHN FLEISCHMANN, a subject of the King of Bavaria, residing at Baltimore, in the State of Maryland, have invented certain new and useful Improvements in Machines for Polishing or Smoothing Moldings, &c.; and I do hereby declare the following to be a full, clear, and exact description of the invention, such as will enable others skilled in the art to which it appertains to make and use the same.

My invention relates to certain improvements in machines for polishing or smoothing wood; and it has for its objects to polish or smooth both curved and plane surfaces at one and the same time or singly, as the case may be. These objects are attained by the mechanism illustrated in the accompanying drawings, in which—

20 Figure 1 represents a side elevation of my improved machine; Fig. 2, a top plan view of the same; Fig. 3, a view in cross-section of one form of polishing or smoothing block; Fig. 4, a similar view of another form of polishing or smoothing block; Fig. 5, a detail view of the block-holder.

Similar letters and figures refer to similar parts throughout the several views.

Reference-numerals 1 2 3 4 indicate the 30 pieces forming the sides of the frame, and 5 and 6 the pieces forming the ends thereof. The top is composed of two pieces A A', having a longitudinal space *a* between their inner edges, in which space is located a longitudinal beam B, the purpose of which will presently appear. A horizontal power-shaft C, journaled in suitable bearings secured to one end of the frame, is provided with band-pulleys D and E, the pulley D being connected by a band F with a pulley G, secured on a vertical shaft H, journaled in suitable bearings secured to the opposite end of the frame, and the pulley E connected by a band I with a pulley K, secured on a vertical shaft 40 L, journaled in suitable bearings secured to cross-pieces 7 and 8, respectively.

Secured to the longitudinal beam B is a guideway-frame M, composed of two vertical posts *m m* and two horizontal guide-pieces 50 *m' m'*, between which operates a reciprocating block N, provided with a slotted end *n*,

which receives one end of a connecting-link O, the other end being attached to a crank-arm P, secured upon the upper end of the vertical shaft H.

55 Adjustably secured to the reciprocating block N is a polishing or smoothing block holder R, having one end slotted at *r*, and provided with perforations *r' r''*, as shown in Fig. 5. This holder is attached to the outer side of the reciprocating block by a binding-screw *r³*, and can be adjusted to any desired height. The polishing or smoothing blocks S S' (shown in Figs. 3 and 4) are attached to the holder by means of binding-screws working through the perforations *r' r''*, and are of a form to correspond with that of the work to be operated upon. The operating-surfaces of these blocks are covered with a suitable polishing or smoothing material, which, if it 60 be sand-paper or emery-cloth, is held by springs *x x* and by strips or cleats secured in place by screws.

65 Located opposite to the guideway M is a curved guideway T, carrying a reciprocating block V, provided with two oppositely-projecting arms *v' v''*. Adjustably secured to said block is a holder *v*, similar to holder R, carrying blocks W W' for polishing or smoothing curved or convex and concave surfaces, 70 it being understood that the blocks S S' are for polishing or smoothing straight or plane surfaces. A connecting-link *w* connects either arm *v'* or *v''* with the crank-arm P, said link being provided with a series of holes near its 75 outer end, as shown, in order to lengthen or shorten the stroke. In polishing or smoothing concave surfaces the guideway T is reversed, as shown by dotted lines in Fig. 2, and the connecting-link *w* shifted to arm *v''*. 80 85 90 95

A vertical shaft Y, journaled in suitable bearings secured to the side pieces of the frame, carries on its upper end a polishing or smoothing wheel *y*, and receives power from the shaft L by means of a belt *y'*. Polishing-wheels of different sizes and with various styles of peripheries may be used on this shaft. Power being applied to the shaft C by means of the crank *c* or a pulley, (not shown,) the polishing or smoothing blocks are 100 reciprocated at either a high or low rate of speed, as may be desired. The work to be

operated upon is held up against the said polishing or smoothing blocks and manipulated by hand.

It is obvious that the reciprocating blocks and wheel may be operated all at the same time or singly, as desired.

Having thus fully described my invention, what I claim as new, and desire to secure by Letters Patent, is—

- 10 1. In a machine for polishing straight and curved surfaces, the combination, with a supporting-frame, of a straight guideway provided with a reciprocating block and interchangeable polishing-blocks, a reversible curved guideway provided with a reciprocating block and suitable polishing-blocks, the shaft H and its crank-arms, the connecting-links for connecting the reciprocating blocks to the crank-arms, and mechanism, substantially as described, for operating the said blocks either singly or simultaneously, as specified.
- 15 2. In a machine for polishing straight and curved surfaces, the combination, with a supporting-table, of a straight and curved guideway mounted thereon, each of said guideways provided with a reciprocating block and interchangeable polishing-blocks, the shaft H and its crank-arms, the connecting-links for connecting the reciprocating blocks to the crank-arms, one of said links being

provided with holes, whereby the stroke may be shortened or lengthened, and mechanism, substantially as described, for operating said blocks either singly or simultaneously, as 35 specified.

3. In a machine for polishing straight and curved surfaces, the combination, with a supporting-table, of a straight and curved guideway mounted thereon, each of said guideways provided with a reciprocating block carrying interchangeable and adjustable polishing-blocks, and connecting-links for connecting the reciprocating blocks with mechanism, substantially as described, for operating 40 said blocks either singly or simultaneously, as specified.

4. The combination, with the supporting-frame having a straight guideway, and with a curved guideway mounted thereon, said 50 guideways being provided with polishing-blocks, of connecting-links O and W, connecting said blocks with mechanism, substantially as described, for operating said blocks either singly or simultaneously, as specified. 55

In testimony whereof I affix my signature in presence of two witnesses.

JOHN FLEISCHMANN.
